RECEPTACLE AND CLOSURE THEREFOR

John Carlind Browne, New York, N. Y.; Katherine G. Browne, administratrix of said John C. Browne, deceased, assignor to Katherine G. Browne, New York, N. Y.

Application June 18, 1941, Serial No. 398,681

4 Claims. (Cl. 215—38)

1

This application is a continuation in part of application Serial No. 251,312, filed January 17 1939.

My invention relates to a new and improved combination of a receptacle and a closure therefor.

One of the objects of the invention is to provide a cap for glass jars, bottles or the like which are sealed under vacuum, whereby the vacuum can be readily broken without distorting the cap to any substantial extent and without chipping the glass, and whereby the cap can be used for sealing the contents after the vacuum has been broken.

Another object is to provide simple means which can be manufactured at low cost and which can be used in a simple and convenient manner.

More particularly the invention embodies a combined glass container and metallic closing cap so arranged and constructed that with the ordinary conventional kitchen tools the housewife may break the vacuum to remove the cap without chipping the glass and with the greatest facility, while the cap may be re-inserted to form a substantially tight closure notwithstanding the vacuum-breaking and cap-removing operation.

Other objects of my invention will be set forth in the following description and drawings which illustrate a preferred embodiment thereof, it being understood that the above statement of the objects of my invention is intended generally to explain the same without limiting it in any manner.

Fig. 1A is a plan view of the invention;

Fig. 2A is a section along the line 2A of Fig. 1A;

Fig. 3A is a section along the line 3A of Fig. 1A;

Fig. 4A is a side view with parts broken away;

Fig. 5A is a view of the embodiment of Figs. 1A to 4A illustrating the relative rotation after the vacuum is broken; and

Fig. 6A is a perspective view showing the breaking of the vacuum by the use of an instrument T.

Closures for glass receptacles utilized in the marketing of food products have heretofore been proposed wherein means are provided for facilitating the removal of the closure cap. These proposals usually involve the use of a sharp or other tool for prying off the cap, and in all such prior proposals with which I am familiar the construction is such as to necessitate the tool coming into chipping contact with the glass with the attendant danger of glass chips entering the

2

food product, or no provision is made to minimize or obviate this danger.

This invention relates to food container closures, particularly adapted for vacuum packed food products, and takes into account the danger of glass chipping by the closure removing tool and minimizes or entirely obviates this danger. It further involves the permanent upsetting or mutilation of a part of the closure for the purpose of breaking the vacuum preliminary to removing the closure with provision for reclosure after the removal to prevent or reduce the likelihood of contamination of food remaining in the container.

15 Referring to Figs. 1A to 6A of the drawings, the invention is illustrated as embodied in a glass jar J' whose neck or mouth portion 1' is indicated as having the finish illustrated, being of conventional structure. According to this 20 conventional structure the upper or end peripheral edge of the neck portion is indicated as having a central substantially flat portion and the rounded edges 17 and 18. The peripheral edge 17 merges into a substantially flat outside surface and this merges into a rounded holding surface or shoulder 20. The jar is provided on its end peripheral edge with shallow lateral recesses 4', the sides of these recesses being curved as indicated at 15 and 16. In the particular embodiment shown there are four of these recesses 4', and this is the preferable number for the reasons indicated below. These recesses are comparatively shallow and are exaggerated in depth as shown in the drawings to correspond to the enlarged scale of the drawings.

35 The closure includes a metallic cap having a disc or bottom 5' and an annular flange 12 formed integral therewith, the flange engaging the flat side periphery of the neck of the jar or container.

40 The lower part 13 of the flange 12 is curved inwardly to engage the rounded holding surface or shoulder 20 formed in the glass container and the edge of the flange is formed into a reinforcing bead 14. The closure also includes a sealing 45 composition 21 which according to conventional practice may be fixed to and carried by the closing cap. This seal may be of composition paper or composition rubber or composition cork and is compressed tightly between the end peripheral 50 edge of the neck 1' of the glass jar and the disc 5' of the cap. Under the pressure of the closure and due to the nature of the sealing composition the latter completely fills up the lateral recesses 4' formed on the end peripheral edge of the jar. As indicated, any suitable composition may be em-

ployed and any conventional practice of forming the seal and applying the cap closure to the jar may be followed so as to pack and house the food in the container under a vacuum. The engagement of the cap flange 12, 13 with the neck 1' of the jar assists the atmospheric pressure in holding the cap in the sealed position.

The metallic cap includes one or more elongated indicium slots 9' which are formed in the flange 12 and are aligned with those parts of the sealing compound or composition 21 contained in the recesses 4'. As indicated in the drawing, the lower wall of a slot 9' is disposed above the level of the bottom of the recesses 4' and likewise the upper wall of the slots 9' is spaced below the disc 5'. Similarly, the end walls of the slots 9' preferably stop short of the end walls 15, 16 of the recesses 4'. These slots 9' serve the double function as indicia to indicate to the housewife where an instrument T, such as an ordinary kitchen knife, may be inserted to break the vacuum in the container and remove the closing cap, and also function to accommodate the reception of this instrument. This instrument T is inserted through the indicium slot 9' and the sealing composition 21 contained in the recess 4' is pierced by this instrument to break the vacuum, whereupon the instrument or knife T may be lifted as indicated in Fig. 6A with the composition in the bottom of recess 4' forming a fulcrum to pry the side of the closure cap with the flange 13 disengaged from the holding surface 20. By reason of the arrangement and structure shown the vacuum may be broken and the cap removed without the knife engaging the glass walls of the lateral recess 4', thus completely eliminating the danger of chipping off glass particles from the glass during this operation. By providing a multiplicity of these lateral recesses and co-operating slots 9' the housewife may insert the knife T into each of these slots and through the composition contained in each of the recesses 4' and the cap is thereby pried off gradually without distorting the same.

After the vacuum is broken and the cap removed the housewife may readily replace the cap upon the jar and reclose the same, and a substantially tight closure is obtained notwithstanding the puncture of the sealing compound in alignment with the slots 9', since upon replacement the cap is rotated as indicated in Fig. 5A relatively to the jar with the slots 9' out of alignment with the recesses 4'. The jar neck as shown in the drawings is not provided with a bead below the holding shoulder 20, but it is understood that it may be so provided with the conventional bead. A sharp round instrument may be utilized in the place of the knife T, but a flat instrument is preferable with a sharp point. The reclosing may be assisted by reheating the product and creating a slight vacuum inside the container whereupon with the cap in the position shown in Fig. 5A the holding and closure is assisted by the atmospheric pressure. It is understood that while the indicium slots 9' are indicated as elongated, slots of any suitable character may be substituted therefor.

I claim:

1. In combination, a receptacle of frangible material for food formed with a substantially cylindrical neck and an annular holding surface disposed adjacent said neck, said neck having a lateral recess formed on the end peripheral edge thereof, a cap for said receptacle comprising a disc shaped top wall and a cylindrical flange integral with said top wall and snugly engaging the

side walls of said neck, said flange having an inwardly projecting part integral therewith and engaging said holding surface, said cap carrying a sealing composition which is compressed between the cap and the end periphery of the receptacle with the composition filling up said recess and forming a tight seal all the way around the neck of the periphery, said flange having a slot indicium registering with the sealing composition in said recess which is formed in the periphery of said neck, and being adapted to receive an instrument for piercing the sealing composition contained in said recess without the instrument engaging the frangible material of the neck and thereby break the vacuum in the receptacle, said cap upon breaking of the vacuum being re-insertable on the neck of the receptacle to reclose the same by pressing the cap upon the neck with the cap rotated relatively to the neck from its original position through a sufficient angle to bring the indicium out of alignment with said recess.

2. In combination, a receptacle of frangible material for food formed with a substantially cylindrical neck and an annular holding surface disposed adjacent said neck, said neck having a lateral recess formed on the end peripheral edge thereof, a cap for said receptacle comprising a disc shaped top wall and a cylindrical flange integral with said top wall and snugly engaging the side walls of said neck, said flange having an inwardly projecting part integral therewith and engaging said holding surface, said cap carrying a sealing composition which is compressed between the cap and the end periphery of the receptacle with the composition filling up said recess and forming a tight seal all the way around the neck of the periphery, said flange having a slot indicium registering with the sealing composition in said recess which is formed in the periphery of said neck, and being adapted to receive an instrument for piercing the sealing composition contained in said recess without the instrument engaging the frangible material of the neck and thereby break the vacuum in the receptacle, said cap upon breaking of the vacuum being re-insertable on the neck of the receptacle to reclose the same by pressing the cap upon the neck with the cap rotated relatively to the neck from its original position through a sufficient angle to bring the indicium out of alignment with said recess.

3. In combination, a receptacle of frangible material for food formed with a substantially cylindrical neck and an annular holding surface disposed adjacent said neck, said neck having a lateral recess formed on the end peripheral edge thereof, a cap for said receptacle comprising a disc shaped top wall and a cylindrical flange integral with said top wall and snugly engaging the side walls of said neck, said flange having an inwardly projecting part integral therewith and engaging said holding surface, said cap carrying a sealing composition which is compressed between the cap and the end periphery of the receptacle with the composition filling up said recess and forming a tight seal all the way around the neck of the periphery, said flange having a slot indicium registering with the sealing composition in said recess which is formed in the periphery of said neck, and being adapted to receive an instrument for piercing the sealing composition contained in said recess without the instrument en-

gaging the frangible material of the neck and thereby break the vacuum in the receptacle, said cap upon breaking of the vacuum being re-insertable on the neck of the receptacle to reclose the same by pressing the cap upon the neck with the cap rotated relatively to the neck from its original position through a sufficient angle to bring the indicium out of alignment with said recess, the lower wall of the slot being above the level of the bottom of the recess and the end walls thereof stopping short of the end walls of the recess.

4. In combination, a receptacle of frangible material for food formed with a substantially cylindrical neck and an annular holding surface disposed adjacent said neck, said neck having a lateral recess formed on the end peripheral edge thereof, a cap for said receptacle comprising a disc shaped top wall and a cylindrical flange integral with said top wall and snugly engaging the side walls of said neck, said flange having an inwardly projecting part integral therewith and engaging said holding surface, said cap carrying a sealing composition which is compressed between the cap and the end periphery of the receptacle with the composition filling up said recess and forming a tight seal all the way around the neck of the periphery, said flange having a slot indicium registering with the sealing composition in said recess which is formed in the periphery of said neck, and being adapted to receive an instrument for piercing the sealing composition contained in said recess without the instrument engaging the frangible material of the neck and thereby break the vacuum in the receptacle, said cap upon breaking of the vacuum being re-insertable on the neck of the receptacle to reclose the same by pressing the cap upon the neck with the cap rotated relatively to the neck

from its original position through a sufficient angle to bring the indicium out of alignment with said recess, said cap being liftable on one side to disengage the inwardly projecting part from the holding surface by means of the instrument which is inserted through the slot and through the body of sealing composition in the recess to break the vacuum and the neck of the receptacle being formed with a smooth interior surface all the way around.
